UNITED STATES PATENT OFFICE.

JOHN A. KELLY, OF PHILADELPHIA, PENNSYLVANIA.

MACHINE FOR AFFIXING LININGS TO SHOE-SOLES.

1,134,619.

Specification of Letters Patent

Patented Apr. 6, 1915.

Application filed March 17, 1914. Serial No. 825,214.

To all whom it may concern:

Be it known that I, JOHN A. KELLY, a citizen of the United States, residing at Philadelphia, county of Philadelphia, and State of Pennsylvania, have invented a certain new and useful Machine for Affixing Linings to Shoe-Soles, of which the following is a specification.

In the process of making shoes, boots, and the like, it is usual to apply a lining of one form or another to that face of the sole or insole which is exposed within the shoe upper. Various forms of linings are employed, such as over the heel, over the heel and shank down to the ball of the foot, or the full length of the sole or insole, such linings being composed of different materials and being called "sock linings" in the trade. It is the custom, and in fact almost the universal practice, to apply such linings to the soles by hand labor, and in the following manner: The operator wields a paste brush in one hand and grasps the lining in the other hand, so that an adhesive is applied to one face of the lining by the proper manipulation of the brush. The upper having been turned down so as to allow access to be obtained to the sole or insole inside of the shoe, the operator applies the pasted lining to the insole or sole at the proper position, after which pressure is applied to the lining so as to smooth out the lining and complete the work. Aside from the time consumed and the labor involved in applying the adhesive and placing the coated lining in position, the hand operations require the upper to be turned for obtaining access to the sole, and it happens not infrequently that the lumps of paste are applied by the brush to the linings. As a result of these two operations, the cost is increased by turning the upper, and the shoe is distorted more or less from the shape imparted thereto by the last, and the presence of lumps of adhesive on the lining produces an irregular surface instead of a smooth surface on the lined sole or insole.

It is the object of this invention to overcome the foregoing objections and others incidental to the hand operation of applying the lining to the soles of shoes, etc., and at the same time to enable the operation of affixing the lining to be performed accurately, expeditiously and economically.

The invention consists of a combined shoe support and magazine over which the shoe

or boot is adapted to be slipped so that the lining will be applied to the face of the sole or insole in a proper manner and without turning the upper. With this magazine and support co-operates means for applying an adhesive to the topmost lining contained within the magazine, and means for feeding the linings successively into the path of the adhesive applying mechanism.

Other features of the invention and the advantages thereof will appear in the course of the following detailed description.

In the drawings, Figure 1 is a side elevation of a machine for affixing sock linings to the sole or insole of boots, shoes, etc., certain parts being illustrated in vertical section. Fig. 2 is a view of the automatic operating means for the adhesive applying mechanism. Fig. 3 is a detail view of the combined support and magazine, illustrating a part of the automatic feed mechanism for the follower. Fig. 4 is a detail plan view of the magazine.

The several working parts of the machine are mounted on a suitable framework herein shown as a column A, a table B, and an overhanging arm C. The table extends outwardly from the column at a height suiting the convenience of the operator, and upon this table is a combined shoe support and magazine D, the latter occupying normally a stationary position upon the table at the outer or free edge thereof. This magazine is of a shape and size suitable to contain in its chamber a large number of linings, the latter being indicated at X. The support and magazine conform substantially in horizontal cross section to the linings X to be stored therein. Within the lower part of the magazine operates a follower E, the purpose of which is to feed the linings toward the open upper end of said magazine, and to this end automatic means are provided for imparting a step by step feed to the stack of linings within said chambered magazine. Upward movement of the linings, however, is resisted to a certain extent by means positioned at the open delivery end of the magazine, which resisting means acts to distort the topmost lining X so that the middle part of the topmost lining will protrude beyond the top of the magazine. The retaining means at the delivery end of the magazine may be of different forms, but as shown the magazine is provided at its respective sides

with lips *e*, the latter extending inwardly with respect to the opening in the delivery end so that the lips will engage with the respective side edges of the topmost lining. 5 Various devices may be employed for imparting the step by step feed to the follower *E*, and while it is not desired to confine the invention to any particular feed means, I have shown one of such feed means in Figs. 10 1 and 3 of the drawings. Depending from the follower *E* is a rack *F*, the same being provided with gear teeth at one edge thereof. The rack passes loosely through a guide *f* depending from the table and in alinement 15 vertically with the magazine. A gear *G* is in mesh with the teeth of the rack, said gear being carried on a horizontal shaft *g* which is journaled in suitable bearings provided on the guide *F*. Said horizontal shaft is 20 provided with a ratchet *H* with which operates a check pawl *I* and a feed pawl *J*, said check pawl acting to prevent the ratchet from turning in a direction which will lower the rack and the follower under the weight 25 of the load imposed upon said follower. The feed pawl is pivoted to an arm *J'*, the latter being loosely mounted on the shaft *g*, and to this arm is connected the upper end of a vertical rod *j*, the lower end of which 30 rod is pivoted to a lever or treadle *K*. Said treadle is pivoted intermediate its ends by a pin *k*, and the free end of the treadle is held in a raised position by a spring *K'*, the latter being secured at one end to the base *a* of the 35 column, whereas the upper end of said spring is attached to the connecting rod *j* between the treadle and the feed lever or pawl *J*.

The adhesive is applied to the exposed surface of the topmost layer of material *X* contained within the magazine by an automatic coating mechanism, one embodiment of which is illustrated in Figs. 1 and 2 of the drawings. Said coating mechanism 40 includes a receptacle *L* which is shown as being supported by a fixed post *l* fastened to table *B*. The receptacle occupies a stationary position at one side of the support and magazine, and in one form of the invention 45 said receptacle is adapted to be charged or filled with absorbent material, such as sponge indicated at *l'*, which absorbent material is charged or filled with the adhesive. Cooperating with the receptacle is a brush 50 *M*, the latter being supported for movement relative to the receptacle, and the combined support and magazine, as shown in Fig. 1, whereby the brush is adapted to sweep over the magazine and the receptacle. The brush 55 is carried by an arm *m* mounted for movement on the overhanging arm *C* by a pin *m'*, or if desired a universal joint may be employed for connecting the swinging brush arm with the frame member. The brush is 60 operated by automatic mechanism, which

automatic mechanism is under manual control so that the brush may be started into operation, whereupon the automatic mechanism becomes effective in imparting a traversing movement to the brush so that it will 70 sweep across the sock lining in the magazine and returned to the position over the paste receptacle. One form of the automatic mechanism embodies a pulley *O* which is mounted on a shaft *o* in the bearing *o'* of a 75 hanger *O'*. This pulley is constantly driven from any source of power; as shown, a belt *p* engages with the pulley *O*, and this belt is driven from a pulley *p'* operated by an electric motor *P*, but, obviously, pulley *O* may 80 be driven from a line shaft or any other source of power. Mounted loosely on the pulley shaft *o* is a crank disk *Q*, the same being provided with a crank pin *q* to which is connected one end of a rod *q'*, the other end of which is pivoted by a pin *q''* to the swinging brush *M*. The crank disk *Q* is 85 adapted to be driven from the rotating pulley *O*, and to this end means are provided for clutching said part *Q* to said part *O*, 90 said clutch means being manually controlled. In one embodiment of the clutch a dog *R* is pivoted to the crank disk by a pin *r*, said dog being provided with an arm *r'* which passes 95 through an aperture *s* in the crank disk. The free end of this arm *r'* is adapted to enter a socket *s'* provided in pulley *O*, and to keep the dog of the crank disk in engagement with the socket of the pulley a spring *S* is attached to the crank disk so as to exert 100 pressure on the pivoted dog *R*. The dog is provided at the end opposite to the arm *r'* with another arm *t*, and with this arm *t* is normally engaged a releasing lever *T*, the latter being pivoted by a pin *t'* on the frame 105 *A*, and said arm *T* is held by a spring *T'* normally in the path of the arm *t* of the pivoted dog. To the arm *T* is attached the upper end of a cord *u*, which is shown as 110 passing beneath a direction sheave *u'* mounted on the frame, said cord *u* being attached to a controlling lever *U* which is fulcrumed on the table *B* at a point convenient to the operator. 115

The operation is as follows: The magazine having been charged with the sock linings, and the pulley *O* being in motion, the operator pulls the lever *U* so as to move the lever *T* and withdraw it from the dog *R*, whereupon the spring *S* presses the arm *r'* of the dog into the socket of the pulley. The crank disk is thus connected to the pulley and motion is imparted to the brush *M* for the purpose of moving said brush 120 from the receptacle *L* across the magazine, and to return said brush *M* back to the receptacle, at which time the lever *T* engages with the arm *t* of the pivoted dog *R* so as to turn said dog on its pivot against the tension of spring *S*, thereby withdrawing 125 130

the arm r' from the socket of the pulley, the effect of which is to automatically move the brush M once across the magazine and to return said brush to position over the 5 paste receptacle and into contact with the material l' therein. The adhesive having been applied to the topmost sock lining of the magazine the operator now positions a boot or shoe Y , indicated in dotted lines in 10 Fig. 1, over the support and magazine and presses the boot or shoe forcibly against the topmost sock lining X within the magazine, whereby the coated surface of the sock lining adheres to the face of the sole or insole 15 within the boot or shoe. The sock lining is thus applied to the boot or shoe in proper position therein without requiring the operator to turn the upper of said boot or shoe, the operation being performed easily, 20 quickly and accurately, for the reason that the magazine serves as a guide in placing the shoe in position to receive the sock lining. The shoe is now withdrawn from the magazine, whereupon the operator presses on the treadle K , the effect of which is to pull down on the rod j and the pawl carrier J' , whereby the feed pawl J is forcibly depressed and the ratchet wheel H is turned a certain angular distance, usually one tooth. This partial rotation of the ratchet wheel turns the shaft g and gear G , the latter meshing with the rack F so as to impart upward movement to said rack and the follower E , as a result of which the stack or pile of sock linings is raised within the magazine, and the topmost layer of the sock linings is engaged with the lips e of the magazine, thus imparting a curved or crowned effect to said topmost layer. The machine is now ready for a second operation, but prior to placing the boot or shoe into position, the operator should first manipulate the hand lever U in order that the brush M will apply the adhesive to the next sock lining. The operations are repeated as often as desired.

It is evident that the operator is not required to handle the adhesive applying mechanism or the material composing the sock linings, and the machine is capable of operation by an unskilled laborer in a manner to accurately, expeditiously and economically apply the sock linings to shoes, boots, and other articles of footwear.

By reference to Figs. 1 and 3 of the drawings it will be noted that follower E is provided at its top surface with a layer of cushion material E^2 , the latter consisting of rubber, or any other soft material. The layer of cushion material permits a certain amount of yielding movement of the sock linings X with reference to the solid material of the follower E , the same being particularly useful when the follower is at the top of the magazine so as to permit the

sock linings to yield somewhat during the application of the adhesive to the topmost sock lining. It is apparent that the layer of cushion material E^2 may or may not be used.

Having thus fully described the invention, what I claim as new and desire to secure by Letters Patent is:

1. In a machine of the class described, the combination of a combined magazine and shoe support for containing linings adapted to be affixed to a sole, said magazine being open at the top thereof, means for feeding said linings within said magazine and shoe support, and coating mechanism positioned to traverse the open end of said magazine and shoe support.
2. In a machine of the class described, the combination of a support over which shoes are adapted to be positioned for receiving a sole lining, means for feeding sole linings relatively to said support in such manner that each lining is positioned for contact with the face of a shoe sole, and means for applying an adhesive to said sole linings.
3. In a machine of the class described, the combination of a support over which shoes are adapted to be positioned for receiving a sole lining, and means for automatically feeding sole linings relatively to said support in such manner that each lining is positioned for contact with a face of a shoe sole.
4. In a machine of the class described, a combined support and magazine over which a shoe is adapted to be positioned for receiving a sole lining, combined with means for feeding the sole linings through the magazine and into position to be affixed to a face of the shoe sole.
5. In a machine of the class described, a combined support and magazine over which a shoe is adapted to be positioned for receiving a sole lining, combined with means for feeding the sole linings through the magazine and into position to be affixed to a face of the shoe sole, and means for applying an adhesive to the exposed face of the topmost lining within the magazine.
6. In a machine of the class described, a combined support and magazine over which a shoe is adapted to be positioned for receiving a sole lining, combined with means controllable at will for feeding sole linings through said magazine, and means for applying moisture to the face of the topmost sole lining within the magazine.
7. In a machine of the class described, the combination of a combined magazine and shoe support, means for feeding material through it, and means controllable at will for applying moisture to the upper layer of material within said magazine and support.
8. In a machine of the class described, the

combination of supporting means for a shoe, means for feeding sole linings relatively to said supporting means in such manner that said linings are positioned for contact with the shoe soles, and means for coating said sole linings prior to the application of the latter to the inside of a shoe adapted to be positioned against said supporting means.

9. In a machine of the class described, the combination of a magazine and support upon which a shoe is adapted to be positioned, a follower positioned within said magazine and support and movable therein, feed means for imparting a step by step movement to said follower, and coating means for traversing said magazine and support so as to coat the sole linings prior to their application to a shoe.

10. In a machine of the class described, a magazine and support upon which a shoe is adapted to be positioned, said magazine and support being provided with means for imparting a curvature to the upper lining of a stack of linings adapted to be contained therein, combined with means for feeding the stack of linings within said magazine and support, and coating mechanism positioned to traverse said magazine and support.

11. In a machine of the class described, the combination of a magazine and support upon which a shoe is adapted to be positioned, means for feeding material relative to said magazine so as to position said material upon the sole of the shoe, coating means positioned to traverse the material prior to

affixing the latter to the shoe sole, and means controllable at will for imparting movement to the coating means.

12. In a machine for affixing sole linings to shoes, the combination of a magazine over which the shoe is adapted to be positioned, and means for feeding sole linings through the chamber of said magazine so as to automatically position said linings for application to the soles of successively positioned shoes.

13. In a machine for affixing sole linings to shoes, the combination of a magazine over which the shoe is adapted to be positioned, a follower movable within the chamber of said magazine so as to feed sole linings therethrough and to position said linings successively for application to the soles of shoes, and means for imparting a step by step movement to said follower with respect to said magazine.

14. In a machine for affixing sole linings to shoes, the combination of a magazine, the contour of which is such that shoes can be drawn thereover, means operable within said magazine for feeding sole linings through it, and moisture supply means in coöperative relation to said magazine.

In testimony whereof I have signed my name to this specification in the presence of two subscribing witnesses.

JOHN A. KELLY.
